UNITED STATES PATENT OFFICE.

JOSEF HANS WEISS, OF BROOKLYN, AND ROBERT WOTHERSPOON, OF JAMAICA, NEW YORK, ASSIGNORS TO ORBIS PRODUCTS TRADING CO., INC., OF NEW YORK, N. Y.

DETERGENT.

No Drawing.

Application filed August 26, 1921. Serial No. 495,760.

To all whom it may concern:

Be it known that we, JOSEF HANS WEISS and ROBERT WOTHERSPOON, citizens of the United States, residing at, respectively, 55 Brooklyn, in the county of Kings, city of New York and State of New York, and Jamaica, in the county of Queens, city of New York, and State of New York, have invented new and useful Improvements in 10 Detergents, of which the following is a full, clear, and exact specification.

Our invention relates to detergents and refers particularly to detergent soaps.

We have found that cymene and the salts 15 of the sulphoacids of cymene possess extraordinary and highly valuable detergent properties capable of practical application in the production of soaps and similar products.

20 The value of these products for detergent purposes is enhanced by our discovery that they are soluble in saponaceous bodies, thus making them suitable for incorporation with saponified fat and saponified oil soaps with 25 the production of products having detergent values greatly in excess of the soaps not so incorporated.

Without entering into a discussion of the several theories regarding the chemical and 30 physical conditions and reactions incident to detergent bodies and their use, we would state that cymene and these cymene compounds have the characteristics of colloids, possessing high viscosity and low surface 35 tension, in addition to which they possess strong emulsifying properties.

We have found that cymene and the salts 40 of the sulphoacids of cymene may be incorporated with saponaceous bodies, either after, or during, their emulsification, producing resulting compounds, or mixtures, possessing high detergent, antiseptic and germicidal properties.

We have further found that cymene and 45 the salts of the sulphoacids of cymene have strong odor destroying properties and that their use in conjunction with odoriferous saponaceous bodies will destroy the odors, thus producing odorless, or practically odor- 50 less, compounds.

We have found, for example, that when 2% of sodium cymene sulphonic acid are added to a soap composed of saponified fat, the detergent properties of the original saponified fats have been increased 65% and 55 that, at the same time, the resulting product is odorless, antiseptic and germicidal, thus possessing greatly increased value over the original saponified fats.

The addition of cymene and the salts of 60 the sulphoacids of cymene will convert soft soaps, such as oleic acid soaps, into hard soaps, irrespective of whether the cymene or the salt of the sulphoacid of cymene is 65 added during, or after, the production of the soap. This is a most valuable attribute of these chemicals.

By "cymene" we mean either the chemically, or commercially, pure cymene, or the crude cymene of the waste sulphite turpentine, obtained as a by-product in the production of paper.

By "salts of the sulphoacids of cymene" we mean those salts of the mono-, or multi-, sulphoacids of cymene which are dissolvable, 75 or miscible, with the particular saponaceous body with which they are employed, producing results having detergent powers greater than the employed saponaceous body.

Among the salts of the sulphoacids of 80 cymene which we have found particularly valuable are the alkali salts, such as sodium, potassium and ammonium salts of the sulphoacids, although other salts have valuable properties for particular uses.

85 For clearness of definition and classification, we employ the words "cymene bodies" in our claims to mean cymene and salts of the sulphoacids of cymene, as described above.

90 By "saponaceous bodies", as referred to in our specification and claims, we mean saponaceous products obtained from animal and vegetable oils and fats and from their compounds capable of saponification.

95 In the following of our process, cymene or one salt of a sulphoacid of cymene, or a mixture of several, may be employed and a single saponaceous body, or a mixture of several, may also be employed.

We do not limit ourselves to the particular chemicals and steps of process particularly described, all of which may be varied without going beyond the scope of our invention as described and claimed.

What we claim is:

1. A soap containing an alkali salt of a sulphoacid of cymene.

2. A soap containing sodium salt of a sulphoacid of cymene.

Signed at New York, in the county of New York and State of New York, this 24th day of August, 1921.

JOSEF HANS WEISS.
ROBERT WOTHERSPOON.
